(57) **CLAIM**

The ornamental design for a construction member for magnetic construction toy, as shown and described.

DESCRIPTION

FIG. 1 is a frontal perspective view of a construction member for magnetic construction toy having an axis AA¹, BB¹, and CC¹ in phantom lines showing my new design; FIG. 2 is a front view of the construction member for magnetic construction toy shown in perspective in FIG. 1 where the rear view is a mirror image thereof;

FIG. 3 is a top view of FIG. 2 along Axis AA¹ in the direction A to A¹, and is the mirror image of the side view of FIG. 2 along Axis CC¹ in the direction C to C¹, and is the mirror image of the side view of FIG. 2 along Axis BB¹ in the direction B to B¹; and,

FIG. 4 is a bottom view of FIG. 2 along Axis AA¹ in the direction A¹ to A and is the mirror image of the side view of FIG. 2 along Axis CC¹ in the direction C¹ to C, and is the mirror image of the side view of FIG. 2 along Axis BB¹ in the direction B¹ to B.
